CLAIM

The ornamental design for a pocket scale, as shown and described.

DESCRIPTION

FIG. 1 is a bottom, front and right side perspective view of a pocket scale showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a bottom, front and right side perspective view showing the pocket scale in an open state.

(Continued)

The broken lines in the drawings illustrate portions of the pocket scale which form no part of the claimed design.

1 Claim, 9 Drawing Sheets
